UNITED STATES PATENT OFFICE.

ANNA M. SESSIONS, OF CHICAGO, ILLINOIS, ASSIGNOR TO ONONDAGA POTTERY COMPANY, OF SYRACUSE, NEW YORK, A CORPORATION OF NEW YORK.

DESIGN FOR A PLATE OR DISH.

41,427.

Specification for Design.

Patented June 6, 1911.

Application filed March 29, 1911. Serial No. 617,754. Term of patent 7 years.

To all whom it may concern:

Be it known that I, ANNA M. SESSIONS, a citizen of the United States, residing at Chicago, in the county of Cook and State of Illinois, have invented a new, original, and ornamental Design for a Plate or Dish, of which the following is a specification, reference being had to the accompanying drawing, forming a part thereof.

The figure is a plan view of a china or porcelain plate or dish showing my new design.

I claim:

The ornamental design for a plate or dish, as shown.

ANNA M. SESSIONS.

Witnesses:

CHAS. F. GREESON,
J. R. MILLWARD.
